HEAT CONSERVER FOR RANGES

Milledge A. Crossman, Reading, Mass.

Application October 22, 1937, Serial No. 170,319

12 Claims. (Cl. 126—211)

The invention herein set forth is concerned with kitchen ranges and the like, and its object is to conserve the heat of the fire, direct the products of combustion and heated gases from the combustion air so as to heat the oven of the range efficiently and quickly, prevent radiation, convection and leakage losses from the top of the range, and to prevent the gases heated in the combustion chamber of the range from being diluted by cold air seeping into the combustion chamber through cracks in the front of the range and adjacent parts of the range top. In this description the term "kitchen range" is intended to include the stoves which are used in kitchens for cooking and maintaining a supply of domestic hot water, and other stoves of analogous character.

The utility of the invention is most pronounced in connection with ranges designed to burn coal which have been converted to oil burning stoves by the installation of oil burners in the fire pot, and will be explained in the following specification with reference to that use and its combination with such a range. But I wish to make it clearly understood that the principles of the invention are not limited to that use but include all other uses and combinations in which any part of the new features contained in the invention may be applied.

Great numbers of ranges designed to burn coal or wood as the source of heat have been converted to use oil by the installation of oil burning equipment in the fire pot. All the makes of ranges used in considerable numbers follow very much the same pattern and are alike in having a deep fire pot extending across the entire width of the range at one end, which is usually referred to as the front, and in having the top made with a large opening within its rim which is crossed by removable bridge bars so arranged as, when in place, to leave two or more pairs of circular holes which are closed by circular lids. Such lids and bridge bars fit loosely at best, and frequently become somewhat warped. They permit leakage of gases from the fire pot into the room, or leakage of outside air into the spaces beneath the range top, depending on the condition of the fire and placement of the dampers. Inward leakage of air occurs elsewhere as well.

The various oil burners provided for such ranges also follow similar patterns, and practically all of them provide two cylindrical annular burners located beneath the two holes of the stove top which overlie the fire pot. The sur-

rounding conditions require the burners to be set at a height such that the zone of heat generation is in the upper part of the fire pot, and the products of combustion rise rapidly and highly heat the top of the stove, but do not quickly or efficiently heat the oven or the water chamber which is commonly formed in one of the bounding walls of the fire pot and is connected with the storage tank for providing a supply of hot water. The products of combustion tend to pass directly to the outlet flue of the range, and only in small measure or with difficulty can they be directed by the ordinary dampers of the range to pass around the baking oven and heat it uniformly enough and hot enough for proper baking. My observation and information is to the effect that with many ranges in which oil burners are used, it requires both burners to be run for two hours or more to make the oven hot enough for baking those comestibles which require a temperature as high as 400° F. and that with some makes of range it is impossible even to attain that temperature in the lower part of the oven.

I have devised an attachment adapted to be inserted into standard ranges without any change in the structure of the range, by which the difficulties above referred to are overcome and the heat generated by the oil burning equipment is so conserved and efficiently used that the oven may be heated in much less time, the water may be heated hotter and more quickly than heretofore, and all cooking performed with less expenditure of fuel. The attachment may be made in different dimensions to fit different ranges, but its principles are the same in all cases. The invention consists both in the attachment itself, in its various modifications and embodiments, and in the combination of such an attachment with the stove or range in which it is installed. One illustrative embodiment of the attachment is shown in the accompanying drawing in which,—

Fig. 1 is a perspective view of an attachment made of two main parts and a number of auxiliary parts, shown with the main parts disassembled from one another;

Fig. 2 is a plan view of a portion of a cooking range showing my attachment installed therein;

Fig. 3 is a cross section of the range taken on line 3—3 of Fig. 2, but showing only the upper portion of the fire pot and the adjacent oven;

Figs. 4 and 5 are perspective views of two alternatively used covers for lids for the holes which

are provided in the heat conserving attachment over the oil burners;

Fig. 6 is a fragmentary sectional view on a larger scale of the lid shown in Fig. 4;

5 Fig. 7 is a fragmentary cross section of the upper part of the range taken on line 7—7 of Fig. 2.

Like reference characters designate the same parts wherever they occur in all the figures.

10 This heat conserving device consists essentially of a plate of heat refractory material which is placed over the fire pot and to a greater or less extent over the flue between the top of the range and the oven, a short distance below the range 15 top. In practice it is made of a number of pieces adjustably connected to one another in a manner to adapt it to different ranges so as to control the flow of hot gases from the burners and prevent outward leakage of gases and fumes and inward 20 leakage of air through cracks in the top and upper side portions of the range. The embodiment here shown consists of a main plate 10, a rear extension plate 11, and adjustable flange pieces 12, 13, 14, 15 and 16. All of these pieces 25 may be made of sheet metal, and I prefer sheet iron because of its low cost as compared with other metals and its ability to withstand exposure to intense heat and severe temperature changes without substantial deterioration over long periods of time. While other refractory materials than metals may be used, the metals are preferred to non-metals because of their toughness and the 30 fact that plates sufficiently rugged to serve the purpose are at the same time so thin as not to choke the flue in which they are placed. Sheet iron of a thickness from fifteen thousandths to twenty thousandths of an inch is thick enough for the purpose. However, there are no narrow 35 limits within which the thickness of the parts 40 need be confined. Any thickness is suitable which enables the plate to extend horizontally without sagging when supported by its edges, and at the same time leaves sufficient flexibility for two overlapping plates when clamped together in the 45 manner presently described to bear closely against one another at their overlapping edges even though not exactly in the same plane elsewhere. The thickness of the parts as shown in 50 the drawing has been much exaggerated in proportion to their length and width dimensions for clearness of illustration.

The main plate 10 of the heat conserving device is formed with an opening 17 near its rear edge adapted to pass over the stud 18 of the range 55 structure which supports the middle part of the removable bridge 19 of the range top. The angular flanges 12 and 13 are adapted to extend into the narrow spaces between the range top and the opposite side walls, as shown in Fig. 7, 60 and are connected adjustably to the plate 12 by bolts 20 and slots 21 so as to accommodate the device to the exact width of the range. The downturned angular flange 15 is secured adjacent to the front edge of the plate 10 by bolts 22 and 65 the forwardly extending angular flange 16 is secured to the flange 15 by bolts 23. These bolts occupy slots which permit adjustment of the flange 15 horizontally and of the flange 16 vertically. The front edge of the plate is turned 70 up to make an upstanding lip or flange 24.

The flanges 15 and 16 are adjusted so that the height between the top of the lip 24 and the under side of the flange 16 is equal to the height of the opening between the forward rim 25 of 75 the range top and the front wall 26. Practically

all ranges have such an opening, which is closed by a door 27, hinged at its lower edge, and in which there is usually a damper. Leakage of air may occur around the edges of the loosely fitting door and damper, but the flanges here 5 shown prevent dilution of hot products of combustion by air from this source. Accommodation of the plate to the distance between the opening referred to and the stud 18 is provided by making the slot 17 substantially longer than the width 10 of the stud. Leakage of gases and air through the slot is prevented by a disk 29 having a central hole which fits the stud closely, and having an outside diameter larger than the length of the slot. The plate is secured to the disk by bolts 15 30 which pass through narrow slots 31 in the plate at opposite sides of the opening 17 to permit of the necessary adjustment. By making the central hole of the disk 29 fit the upper end of the stud, which is of tapered formation, the disk 20 serves as a suspender for the middle of the rear edge of the plate, preventing this part from sagging. The lip 24 and flanges 12 and 13 establish 25 a space of predetermined depth, in the order of preferably one half inch to an inch, between the plate and the range top; and the nuts on the suspender bolts 30 may be adjusted to bring the rear part of the plate to approximately the same depth.

Holes 32 and 33 are made in the plate 10 directly over the burners 34 and beneath the holes of the range top which are always provided over the fire pot. The edges of these holes are reinforced, preferably by a rod or heavy wire 35 bent into a ring of which the inside diameter is approximately equal to the diameter of the hole, which ring is welded or otherwise suitably secured in a permanent manner to the under side of the plate. Lids 36 are provided for the holes 32 and 33. These are preferably made from disks 40 of the same sheet metal as the plate, larger in diameter than the holes, and having welded to their under side a ring 37 like the ring 35 except that its outside diameter is such that it fits freely within the hole. The lids used most of the time are imperforate; but for some purposes, when a more rapid rise of heat from the burner is desired, a perforated lid 38, shown in Fig. 5, may be substituted for either or both of the imperforate lids. These lids are provided 45 with socket pieces 39 welded or otherwise suitably secured to their upper faces, by which they can be lifted and shifted by the ordinary stove lid lifter.

The foregoing detailed description of the reinforcing means for the holes in the heat conserving device and of the construction of the lids sets forth what I now consider to be the best construction now known to me. But it is not intended to limit the scope in which I claim protection, and I reserve 60 the right to substitute other constructions for those thus described.

The main part 10 of the conservation device is made short in the direction from the front wall 26 toward the opposite or back wall of the stove 65 in order to facilitate installation in a range already in use. It is in effect extended by the plate 11 which overlaps, or may be arranged to overlap if desired, at its front edge the rear edge of the main plate and is secured thereto by 70 bolts 40 passing through registering holes 41 and slots 42 in the respective plates. When thus assembled, the two plates are one in effect. The extension plate overlies the top wall 45 of the baking oven, and may have a length great enough 75

to bring its rear edge all the way out to the rearmost boundary of the oven. Both intermediate edges of the extension plate are provided with offset horizontal flanges to hook over the walls 5 of the range in the spaces adjacent to the top always found in kitchen ranges. One of such flanges is provided by the adjustable angle piece 14 previously described, and the opposite flange 44 may likewise be an adjustable piece, but equally well may be integral with the plate, as shown in Fig. 1.

The heat conserver of this invention is installed in a range after the lids and bridge bars of the range top have been removed. The flange 15 16 of the main plate is properly adjusted as to height, and the plate placed so that said flange rests on the front wall while the lip 24 extends close to, or bears against the range top, and the opening 17 passes over the stud 18. The adjustable flange bars 12 and 13 are adjusted to hook over the inner ledges of the side walls of the range, and the disk 29 suitably adjusted. The extension plate is slipped into place and similarly adjusted, and its overlapping front edge is 20 clamped to the rear edge of the main plate by bolts. The outline of the front plate is made such that its edges approximately fit the interior of the front part of the range. In any case where the fit is not so close as to prevent leakage, asbestos cement may be placed there, and in any other places where cracks appear. The best efficiency with the use of this device is developed by the most complete possible absence of leakage, wherefore it is fitted closely to the bounding 25 walls of the range, and the use of refractory cement is recommended wherever leakage cracks appear. After once being installed no change in the position of the heat conserver is needed throughout its useful life. The bridge bars and 30 lids of the range top may be then replaced, and any of them may be removed and shifted for cooking as desired by the cook.

This device forms a partition extending over the fire space and the adjacent part of the oven, 45 separated from the top of the range by an air space; wherefore it may be designated descriptively as a "partition device". It prevents escape into the outer air of gases and soot from the burners. It very greatly reduces heat losses by 50 radiation and convection from the top of the range by reason of the air space above it and beneath the range top. It reflects heat back into the fire pot and guides the products of combustion from the burner over the oven, preventing 55 escape through the discharge flue until after the hot gases have passed around the oven through the spaces left for the hot gases. Thus the oven is more quickly heated, the water in the water front 45 (or equivalent water containing chamber or coil) is heated to a higher temperature and more quickly, and the generated heat is more 60 completely utilized and less of the available heat allowed to escape up the chimney than heretofore. It has been demonstrated in practice that the oven of a range used for test has been brought to the highest normal baking heat from a cold condition with the use of one burner only in approximately one hour, as compared with two 65 hours lapse of time with the use of two burners required in the same range before the device was installed. The water in the heating chamber or coil is brought from room temperature to a temperature as high as needed for washing in a few 70 minutes by one burner. Dust and soot are car-

ried up the chimney and not released into the room. The cooking utensils used on the top of the stove are not burned or covered with soot.

What I claim and desire to secure by Letters Patent is:

1. The combination with a range having a fire pot and an oven beside the fire pot and containing passageways for hot gases over and around the oven, of a heat conserver consisting of a substantially horizontal partition extending 10 over the fire pot and over the adjacent part of the oven, and separated from the top of the range by an air space.

2. The combination with a range having a fire pot and an oven beside the fire pot and containing 15 passageways for hot gases over and around the oven, of a heat conserver consisting of a substantially horizontal partition extending over the fire pot and over the adjacent part of the oven, and separated from the top of the range by an 20 air space, said partition being heat refractory and substantially impervious to leakage of gas.

3. A heat conserver for use in cooking ranges consisting of a plate of heat refractory material shaped and adapted to be installed over the fire 25 pot and beneath the top of a range.

4. A heat conserver for use in cooking ranges consisting of a plate of heat refractory material shaped and adapted to be installed over the fire pot of the range and beneath the top of the range, 30 said plate having an extension adapted to pass into the flue between the top of the range and the oven top in a location sufficiently below the range top to provide an air space and sufficiently high above the oven top to permit an unchoked 35 flow of products of combustion from the fire pot.

5. A heat conserver for use in cooking ranges consisting of a plate of heat refractory material shaped and adapted to be installed over the fire pot and beneath the top of a range, said plate 40 having an upturned lip and a downturned flange on its forward edge, the collective height of which is sufficient to span the usual space between the front wall and overlying top of a cooking range.

6. A heat conserver for use in cooking ranges consisting of a plate of heat refractory material shaped and adapted to be installed over the fire pot and beneath the top of a range, said plate 45 having an upturned lip at its forward edge, combined with angular flange pieces secured adjustably to its forward edge and to its lateral edges.

7. A heat conserver for use in cooking ranges consisting of a plate of heat refractory material shaped and adapted to be installed over the fire 55 pot and beneath the top of a range, combined with a downturned flange secured to the forward extremity of the plate with provision for adjustment lengthwise of the plate, offset flanges parallel with the plane of the plate extending from its lateral edges, adapted to project between the top and the upper extremities of the opposite side walls of such a range.

8. A heat conserver for use in cooking ranges 65 consisting of a plate of heat refractory material shaped and adapted to be installed over the fire pot and beneath the top of a range, an angle piece having a downturned flange secured to the plate parallel and adjacent to the front edge 70 thereof with provision for adjustment transversely of such edge, and an angle piece having a forwardly projecting flange at its lower extremity secured to said downturned flange with provision for up and down adjustment, said last 75

named flange being adapted to rest on the front wall of a range beneath the overlying part of the top of such a range.

9. A heat conserver for use in cooking ranges consisting of a plate of heat refractory material shaped and adapted to be installed over the fire pot and beneath the top of a range, said plate having a hole in the portion thereof which is adapted to overlie the fire space in a range, combined with a lid having a centering member on its underside adapted to enter the hole and center the lid with its circumference overlapping the rim of the hole.

10. A heat conserver for cooking ranges and the like adapted to be located beneath the top of such a range and over the fire space thereof, comprising a sheet metal plate having an opening adapted to be passed over the bridge supporting stud of such range, the plate having also lateral flanges for engagement with the side walls of a range beneath the top and having at its forward end a downwardly offset flange adapted to be supported on the front wall of a range, said flanges being suitably formed and proportioned

to locate the plate beneath and spaced apart from a range top.

11. A heat conserver for use in cooking ranges consisting of a partition device of heat refractory material shaped and adapted to be installed over the fire pot and beneath the top of such a range, 5 said device having a downturned flange on its forward edge, the height of which is sufficient to extend from such forward edge to the front wall of a range across the usual space between such 10 wall and the range top.

12. A heat conserver for use in cooking ranges consisting of a partition device of heat refractory material shaped and adapted to be installed over the fire pot and beneath the top of such a range, 15 combined with a downturned flange secured to its forward extremity with provision for adjustment lengthwise thereof, and offset flanges extending from its lateral edges adapted to enter between the top and the opposite side walls of 20 such range, said offset flanges and the main portion of the device being relatively adjustable for accommodation to the exact width of a given range.
